Primary Examiner — Kathleen L Jones

(57) **CLAIM**

The ornamental design for a display screen or portion thereof with graphical user interface, as shown and described.

DESCRIPTION

25. Display screen or portion thereof with graphical user interface;

27. Display screen or portion thereof with graphical user interface;

31. Display screen or portion thereof with graphical user interface; and

35. Display screen or portion thereof with graphical user interface.

The outermost solid line rectangle depicts a display screen or portion thereof which forms part of the claimed design; all the broken lines shown in the reproduction figures, including the entire paint can icon, depict portions of the graphical user interface that form no part of the claimed design.

1 Claim, 4 Drawing Sheets
